UNITED STATES PATENT OFFICE.

IRA C. SAXE, OF CHICAGO, ILLINOIS.

ROOFING CONSTRUCTION.

Application filed August 30, 1920. Serial No. 403,952.

To all whom it may concern:

Be it known that I, IRA C. Saxe, a citizen of the United States, and a resident of the city of Chicago, county of Cook, and State of Illinois, have invented certain new and useful Improvements in Roofing Constructions, of which the following is a specification.

My invention relates to improvements in roofing constructions, and has for its object the provision of an improved construction of this character which may be quickly and readily applied to the roof of a building, and which is durable in use and attractive in appearance.

Other objects will appear hereinafter.

The invention consists in the combinations and arrangements of parts hereinafter described and claimed.

The invention will be best understood by reference to the accompanying drawings forming a part of this specification, and in which,

Fig. 1, is a vertical section taken through a portion of a roofing construction embodying the invention,

Fig. 2, a side view corresponding with Fig. 1,

Fig. 3, a view similar to Fig. 1, but showing a slightly modified form of construction,

Fig. 4, a side view corresponding with Fig. 3,

Fig. 5, a perspective view of a portion of a roof embodying the construction,

Fig. 6, a detail view of roofing sheets employed on the hips of a roof, and

Fig. 7, a detail view of a modified form of construction.

The form of construction illustrated in Figs. 1 and 2 comprises roofing members 8, consisting of strips of impregnated felt. Each of the strips 8 is provided at one edge with a re-bent and rolled portion 9, the portion 9 being flattened, as indicated. The

strips 8 are applied to the roof commencing at the lower edge thereof, the lowermost strip being applied first and being extended over the gutter 10, as shown, and secured thereto by nails 11. Then the next strip is applied, with its rolled edge 9 overlapping the upper unrolled edge of the lowermost strip 8, and nails 11 driven through the rolled edge, as shown. Strips 12 of the impregnated felt are arranged over the strips 8, as indicated, to imitate tiling and produce an ornamental effect. The ridge cap 13 is

covered with strips of the impregnated felt, the edge of said strips being turned under the ridge cap, as indicated, and ornamental bands or cuffs 15 of the impregnated felt are also secured around the ridge cap, as shown. The strips 8 are formed at the factory with the rolls 9 along one edge and under uniform conditions of heat, which facilitates the rolling and flattening of the impregnated felt. These strips are then rolled lengthwise and furnished in this form, thus avoiding any necessity for bending the strips of material in the open air when being applied, and whereby breakage or cracking is avoided.

In the modified form of construction illustrated in Figs. 3 and 4, the ornamental strips 12 and cuffs 15 have been omitted, but otherwise the construction is identical with that already described.

In Fig. 6 I have illustrated a form of strip or sheet adapted for use at the hips of a roof. In this construction, sheets 16 of impregnated felt are provided with a simple re-bent edge 17, as indicated, said strips being cut into suitable lengths and laid over the hips, as indicated in Fig. 5.

In the modified form of construction illustrated in Fig. 7, the sheets 8 are provided with simple re-bent edges 18 and an additional strip 19 of the same material folded upon itself is inserted under the re-bent edge 18, such arrangement taking the place of the roll 9 provided on the sheets indicated in Figs. 1, 2, 3 and 4. The edge 18 is bent and the strip 19 applied at the factory under uniform heat conditions, and the strips rolled for transportation as before. Otherwise, the construction is identical with that already described.

While I have illustrated and described the preferred forms of construction for carrying my invention into effect, these are capable of variation and modification without departing from the spirit of the invention. I, therefore, do not wish to be limited to the precise details of construction set forth, but wish to avail myself of such variations and modifications as come within the scope of the appended claims.

Having described my invention, what I claim as new and desire to secure by Letters Patent is:—

1. A roofing construction comprising overlapped sheets of flexible material, the overlapped edge of each sheet being rolled

and flattened upon itself; and laterally disposed uniformly spaced strips of roofing material secured beneath one overlapped edge and extending to and being secured beneath the next overlapped edge of said sheets to provide an effect in imitation of tiling, substantially as described.

2. A roofing construction comprising overlapped sheets of flexible material, the overlapped edge of each sheet being rolled and flattened upon itself; laterally disposed uniformly spaced strips of roofing material secured beneath one overlapped edge and extending to and being secured beneath the

next overlapped edge of said sheets; and 15 cuffs of said roofing material disposed on the ridge cap of a roof and having their ends tucked thereunder and alternating with the adjacent series of laterally disposed strips to provide an effect in imitation of tiling, sub- 20 substantially as described.

In testimony whereof I have signed my name to this specification in the presence of two subscribing witnesses.

IR A C. SAXE.
